UNITED STATES PATENT OFFICE.

JACOB HUBER, OF TOLEDO, OHIO, ASSIGNOR TO CHAS. P. CROSBY AND WILLIAM F. CROSBY, OF CHICAGO, ILLINOIS.

WRENCH.

SPECIFICATION forming part of Letters Patent No. 320,357, dated June 16, 1885.

Application filed February 7, 1885. (No model.)

To all whom it may concern:

Be it known that I, JACOB HUBER, a citizen of the United States, residing at Toledo, in the county of Lucas and State of Ohio, have 5 invented certain new and useful Improvements in Wrenches; and I do declare the following to be a full, clear, and exact description of the invention, such as will enable others skilled in the art to which it appertains to make and 10 use the same, reference being had to the accompanying drawings, and to the letters and figures of reference marked thereon, which form a part of this specification.

This invention relates to that class of inventions commonly known as "monkey-wrenches," 15 and has for its object to provide a simple construction by which the sliding jaw may be readily adjusted to and securely locked at any suitable point.

20 The invention consists, essentially, in the combination, with the shank having a segment of a thread and the sliding jaw, of a locking-sleeve encircling the shank and an extension of the sliding jaw, said sleeve being provided 25 with a segment of a thread.

It further consists in certain novel constructions, which will be hereinafter more fully described, and pointed out in the claims.

In the accompanying drawings, Figure 1 is 30 a side view, part in section, of my wrench. Fig. 2 is a detached section on line x x , Fig. 1. Fig. 3 is a detached section drawn through the arm of the sliding jaw. Fig. 4 is a front end view of the locking-sleeve. Fig. 5 is a 35 detail view of a section of the shank; and Fig. 6 is a detail view of the locking-sleeve, all of which will be described.

The shank a is provided with the usually 40 fixed jaw a' , and has a suitable handle, a'' . This shank is provided on its upper and lower sides with a segment of a thread, a^3 , and its two remaining sides are flattened, as shown. The movable jaw b is placed on and movable 45 along the shank a . It is provided at its rear upper end with a pin, c , for the purpose presently described. This jaw b is also formed with arms i , which extend alongside of the shank a , and are lapped against the flattened sides of such shank, as shown in Figs. 1 and 2. 50 At the rear end of these arms a retaining-ring, f , encircles the shank, and is detachably

connected with the arms i , usually by means of set-screws g . The locking-sleeve d is placed on the shank, and fits between the rear end of the jaw b and the retaining-ring f . This sleeve 55 is provided with an internal segmental thread, h , and with blank spaces h' . The blank spaces h' are of a length equal to the segmental threads a^3 on the shank a .

In operation the sleeve, which may be rotated on the shank a , may be turned so as to 60 make its threads h mesh with the threads a^3 on the shank, or it may be turned so as to bring its blank spaces h' to register with such threads. When adjusted to the latter position, 65 the sleeve d may be moved along the shank a , taking with it the wrench-jaw b , until the latter has been brought to fit on a nut or bolt, when, by turning the sleeve d so as to mesh its threads h with the threads a^3 of the shank, 70 the pitch of such threads will tighten the jaw b against the nut or bolt, and at the same time lock the slide-jaw in position.

While I prefer to use the pitched threads, 75 because by them I secure a tightening as well as locking of the jaw b , it is manifest that the locking of the said jaw might be secured by threads formed at right angles to the length of the shank, in order that the sleeve may be quickly meshed with the threads a^3 . I prefer 80 to form side threads, a^3 , pointed at their ends, as shown in Fig. 5. An equivalent of this construction would be the pointing of the threads h , in order that the sleeve may be stopped. In both its locked and unlocked 85 positions I provide at its forward end shoulders e e , which are arranged on opposite sides of the pin c and engaged therewith when the sleeve is brought to its locked and unlocked position, so that the said sleeve is accurately 90 stopped when its threads have been properly engaged and operated to tighten the movable jaw, and also when the said sleeve is turned in such manner that the threads may clear the threads a^3 , in order to permit the free 95 movement of the sleeve back and forth on the shank.

While I prefer to use two segments of the threads h , and a corresponding number of the threads a^3 , it will be understood that a single 100 set of each of the threads might be employed without departing from the invention, and

where desired the sets of threads may be increased in number, so that the alternate arrangement of blank spaces and threads is preserved.

- 5 The detachable ring *f* serves as a convenient means for retaining the sleeve in proper position on the shank. It is obvious, however, that the said ring may be fixed to the arms *i* and the sleeve *d* be formed in longitudinal sections, hinged at one edge, and provided at their other edges with suitable latch devices; or the said arms *i* and ring *f* might be dispensed with, and the locking-sleeve *d* be connected with the jaw by means of a tongue 10 or projection on the one entering the groove of the other, as is employed frequently in connecting the adjusting-sleeve of the ordinary monkey-wrench to the movable jaw. I prefer, however, to employ the constructions shown, 15 because it may be easily and cheaply made. The arms *i* form a bearing for the locking-sleeve, and such sleeve, being held by the ring *f*, may be quickly removed independently of the jaw, for any desired purpose.
- 20 25 It will be noticed that my wrench may be quickly adjusted to or locked in any desired position by placing the locking-sleeve on and encircling the shank. The said sleeve, in addition to its locking and tightening functions, 30 serves efficiently as a handle by which to set the jaw back and forth, and by reason of its arrangement around the shank it may be readily moved along the shank without any of the clamping or binding actions likely to 35 ensue when the jaw is moved by a construction arranged wholly on one or the other side of the shank.
- Having thus described my invention, what I claim, and desire to secure by Letters Patent, 40 is—

1. The combination of the shank provided with a segmental thread and having its sides flattened, the movable jaw provided with projections, and the locking-sleeve encircling said projections and rotating upon the shank, and provided with an internal segmental thread and held to and sliding longitudinally simultaneously with the said jaw, whereby the latter may be adjusted along and locked at any desired point on the shank, substantially as 45 set forth.

2. The combination of the shank provided with a segmental thread and having its sides flattened, the sliding sleeve encircling and rotating upon the shank, and provided with an internal segmental thread and having stop-shoulders on its end next the movable jaw, the movable jaw held to and movable simultaneously with the sliding sleeve, and a check-pin or stop arranged on the jaw to engage 55 with the stop-shoulders on and limit the rotation of the sleeve, substantially as set forth.

3. The combination of the wrench having two of its opposite sides flattened and provided with a segmental thread, the movable 65 jaw having arms lapped along the flattened sides of the shank, the locking-sleeve encircling the shank having an internal segmental thread, and the retaining-ring encircling the shank in rear of the locking-sleeve and detachably connected with the arms of the 70 movable jaw, substantially as set forth.

In testimony whereof I affix my signature in presence of two witnesses.

JACOB HUBER.
